US00D964007S

(12) **United States Design Patent** (10) **Patent No.:** **US D964,007 S**
(45) **Date of Patent:** **** Sep. 20, 2022**

(54) **ARTICLE OF FOOTWEAR**

(71) Applicant: **New Balance Athletics, Inc.**, Boston, MA (US)

(72) Inventor: **Charlotte Lee**, Manchester (GB)

(73) Assignee: **New Balance Athletics, Inc.**, Boston, MA (US)

(**) Term: **15 Years**

(21) Appl. No.: **29/778,069**

(22) Filed: **Apr. 9, 2021**

Related U.S. Application Data

(63) Continuation of application No. 29/743,796, filed on Jul. 24, 2020.

(57)

CLAIM

The ornamental design for an article of footwear, as shown and described.

DESCRIPTION

FIG. 1 is a lateral side view of an article of footwear; FIG. 2 is a top view thereof;

FIG. 3 is a medial side view thereof;

FIG. 4 is a front view thereof;

FIG. 5 is a rear view thereof;

FIG. 6 is a front perspective view from the lateral side thereof; and,

FIG. 7 is a rear perspective view from the lateral side thereof.

The short, broken lines shown in the drawings of the article of footwear illustrate portions or stitching that form no part of the claimed design.

1 Claim, 7 Drawing Sheets
